UNITED STATES PATENT OFFICE.

FREDERICK L. FULLER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

MULTIPLE CASH-REGISTER.

1,117,179.

Specification of Letters Patent. Patented Nov. 17, 1914.

Application filed December 6, 1910. Serial No. 595,857.

To all whom it may concern:

Be it known that I, FREDERICK L. FULLER, a citizen of the United States, residing at Dayton, in the county of Montgomery and State of Ohio, have invented certain new and useful Improvements in Multiple Cash-Registers, of which I declare the following to be a full, clear, and exact description.

This invention relates to cash registers accomplishing the usual functions of multiple totalizer cash registers, namely in totalizing according to classes the different transactions entered in the register, in making printed records of transactions and temporarily indicating similar data concerning each transaction. It differs from other two-motion cash registers, that is, registers, which to operate, first require manipulation of amount and special setting devices such as transaction keys and then the operation of driving mechanism, in construction and in an arrangement whereby class of transaction selecting devices also serve for the application of driving power to the machine, having for its object the saving of one manual operation for each entered transaction. It is customary in two-motion cash registers to have a set of amount determining and a set of transaction determining devices and a single device for transmitting power, such as a crank lever or motor of some kind.

This invention provides a cash register with a plurality of such power devices, each of which also acts as a transaction determining device.

Another object of the invention is to provide an improved form of differential mechanism for actuating multiple totalizers.

Another object of the invention is to provide an improved arrangement of tablet indicators, for reading from both sides of the machine, whereby each tablet is in the correct denominational position.

Another object of the invention is to provide an improved full stroke device for compelling a complete operation of the machine before a succeeding operation can take place.

With these and incidental objects in view, the invention consists in certain novel features of construction and combinations of parts, the essential elements of which are set

forth in appended claims, and a preferred form of embodiment of which is hereinafter described with reference to the drawings which accompany and form part of the specification.

Figure 1 is a left side elevation of a cash register constructed according to this invention and with the printing mechanism cabinet and supporting frame omitted. Fig. 2 is a detail in left side elevation showing the transmission of the differential movement from the keys to the actuating devices of the machine. Fig. 3 is a front elevation of the differential mechanism of the machine. Fig. 4 is a transverse vertical section of the indicator mechanism taken on the line 4—4 of Fig. 5. Fig. 5 is a plan view of the indicator mechanism. Fig. 6 is a front elevation of a carriage for totalizer and indicator actuating slides and printing mechanism. Fig. 7 is a detail in right side elevation of one of the main operating levers and a carriage driven thereby. Fig. 8 is a plan view of part of the mechanism shown in Fig. 7. Fig. 9 is a left side elevation of one of the key detents for the value keys and a locking mechanism operated thereby. Fig. 10 is a detail of a segment which is operated by the value keys including a lock for the "No sale" lever. Fig. 11 is a detail in left side elevation of a key detent for the bank of initial keys and a lock operated thereby for locking the machine temporarily during the depression of an initial key. Fig. 12 is a detail of a segment co-acting with initial keys and by which the regular locking devices of the machine are released. Fig. 13 is a detail in left side elevation of one of the differential racks for actuating the totalizers and part of the totalizer resetting device and co-acting devices. Fig. 14 is a fragmentary front elevation of one of the totalizers. Fig. 15 is a left side elevation of one of the totalizers including one of the racks for operating the same. Fig. 16 is a detail in right side elevation of a full stroke mechanism for the driving shafts of the machine. Fig. 17 is a left side elevation of the printing mechanism. Fig. 18 is a transverse vertical section of the printing mechanism. Fig. 19 is a front elevation of the printing mechanism. Fig. 20

is a left side elevation in detail of the platen for the printing mechanism. Fig. 21 is a plan view of a check strip guide of the printing mechanism. Fig. 22 is a perspective view of the machine.

Having reference to the general plan of the machine, it comprises a plurality of actuating levers by which power is applied to the machine and which serve to select desired totalizers and cash drawers for operation. Each lever when operated locks the remaining levers from operation, and serves to actuate a slide having connections for driving the machine and for selecting a corresponding cash drawer, and has connections for setting the transaction type carrier and one of the transaction indicators, and for rocking a set of totalizer actuating racks into operative position. The said slides are provided with rack teeth meshing with pinions on a main driving shaft and thus serve to rotate the driving shaft, which latter carries pinions meshing with racks on a vertically movable carriage, having stepped slides for engagement with the totalizer actuators, and carrying type wheels for making printed detail records.

The depression of keys serves to differentially set the stepped slides on the carriage, so that when the carriage is elevated the slides will engage and differentially actuate totalizer actuating racks. The stepped slides also have rack teeth for setting type wheels journaled in the carriage, and a platen is mounted above the carriage, and the record and check strips are in such position that the upward movement of the type carriers bears the strips between the type carriers and the platen effecting the desired impression. A second set of slides are mounted in the carriage and are also differentially set by action of the keys and serve to engage indicator tablets for setting the same on the upward movement of the carriage. The indicator tablets are divided into denominational groups arranged in two sets, for being viewed from both the front and rear of the machine.

Operating handles.—Operating handles or levers 19 (Figs. 1 and 22), by which power is applied to the driving mechanism are pivoted on a rod 4, and in number correspond to the different classes of transactions of which the machine is arranged to make records. Each lever 19, which is best shown in Fig. 22, serves for operating the machine when an entry of the particular class of transaction which it represents is made. Looking from left to right on this figure the levers are respectively lettered "No sale", "Paid out", "Charge", "Received on account", and "Cash". That each lever may rotate drive shaft 58 forwardly and backwardly one-half rotation, and shaft 67 forward one-fourth rotation, it is provided

with a slot 20 embracing a circular knob 21 on one of slides 18 each of which has a rack 56 for oscillating a pinion 57 fast to shaft 58 and has connections for effecting a one-fourth rotation of shaft 67. These latter connections consist of pins 17 fast to the slides and extending through slots 16 in arms 15 loose on shaft 67 but having pawl and ratchet connections thereto. The plates 15 carry a set of pawls 73 (Fig. 13) which, upon the return movement of the lever, engage shoulders 74 of a set of disks 66 which are fast to the shaft 67, consequently rotating the shaft 67 counter-clockwise (Fig. 13) one-quarter revolution. The operation of more than one lever 19 at a time is prevented by a number of stops 230 (Fig. 8) resting in a groove 231 in a tie bar 232 and having beveled ends 233 extending into cuts 234 in slides 18. When any lever 19 is operated its slide 18 forces the stops 230 aside far enough to permit the slide to pass, but the stops to the right and left prevent the passage of any other slide 18, until the slide first moved is returned to its normal position. The operations of levers 19 are counted by a counting device 212 (Fig. 1) and to actuate these counters the slides 18 carry pins 213 for engagement with extensions 214 of pawl carrying arms 215 pivoted to the machine frame by pins 216. The counters are of a usual construction and therefore will not be described.

Driving mechanism.—The driving mechanism (Fig. 1) consists of the oscillatory shaft 58, shaft 67, and carriage 55 and a transfer cam shaft 95 having a geared connection to shaft 67. The function of shaft 58 is to lift the carriage 55, this carriage having connections for actuating the totalizers, the printing mechanism, and for setting indicators as will appear farther on. A full stroke device for the drive shaft 58 and the shaft 67 is shown in Fig. 16. The drive shaft 58 first rotates in the direction indicated by the arrow 179 a half rotation and is then returned to normal position. During the forward rocking of the shaft, backward rotation of the same is prevented by a ratchet wheel 180 fast thereon co-acting with a pawl 181 loosely mounted on a short shaft 182 and held in engagement with the ratchet 180 by a spring 183 compressed between the pawl 181 and the bell crank lever 184, also loose upon the shaft 182 and having a nose 185 normally extending into one of four notches 186 in a disk 187 fast to the shaft 67. A spring 188 normally retains the bell crank lever in the position shown in the drawing, but when shaft 58 completes a half rotation a pin 1881, fast to the ratchet wheel 180 and to a ratchet wheel 189, engages an arm 190 of a disk 191 which is loosely journaled on the shaft 58, rocking the arm 190 into engagement with a

nose 192 of the bell crank lever 184, thus rocking the bell crank lever downwardly and holding the same in its moved position by a shoulder 193 of the arm 190 engaging the shoulder 192. The rocking movement of the bell crank lever, through pins 262 passing through holes in the pawls, forces pawl 181 out of engagement with the ratchet 180 and a pawl 194 into engagement with 10 the ratchet 189 so that the return rocking of shaft 58 will be permitted while any attempt to again move the same forwardly will be prevented. As the nose 185 is thus disengaged from disk 187 shaft 67 is free 15 to make its one-quarter rotation upon the return movement of the operating lever 19. When shaft 58 arrives at its home position and shaft 67 has completed its one-quarter turn, pin 1881 engages a shoulder 1882 of disk 191, returning the disk to normal position and thus allowing pawl 181 to again engage ratchet 180, and the nose 185 of bell crank lever 184 to enter one of the notches 186 in disk 187.

25 *Keyboard.*—Each denominational bank of keys 1 and a similar bank of initial keys 260 (Figs. 1 and 22) are carried by removable frames 2, supported in the machine by tie bars 3 and 4. The keys are depressible 30 against the action of springs 5 (Fig. 2) and carry pins 6 co-acting with detents 7, loosely pivoted on rod 26, for retaining depressed keys in their depressed positions during the 35 operation of the machine. The detents 7 are provided with a plurality of inclined projections 8 with which the pins 6 co-act. Thus a detent will be elevated on the depression of a key until the key pin 6 reaches a notch 9 in the detent when the detent 40 springs downwardly under the action of a spring 10 (Fig. 9) thus retaining the key in its depressed position. For the purpose of preventing operation of the machine while a key is being depressed each detent 7 is 45 provided with a downwardly extending arm 11 in position to engage a rod 12 of a frame 13 (Fig. 9) having a number of latching arms 14 co-acting with notches in the plates 15 (Figs. 1 and 13). Each plate 15 as 50 hereinbefore stated is provided with a slot 16 through which extends a pin 17 on one of slides 18 driven rearwardly by the main operating levers 19 as explained, and returned with the levers by springs 236. Consequently when an operating lever is rocked 55 downwardly around its pivot 4 and its corresponding slide 18 is moved rearwardly, the plate 15 is rocked in a clockwise direction. If it is attempted to operate one of the levers 19 while a key is being depressed, the arms 14 of the frame 13 will be in the path of shoulders 22 of the plates 15 and prevent operation of any one of the levers 19. However, if the depressed keys have 60 reached their extreme inner positions where

they become latched, the return movement of detent 7 at such time permits the frame 13 to rock rearwardly thus permitting the operation of one of the levers 19.

It is desired to compel the depression of 70 an initial key before the machine may be operated, consequently the bank of initial keys 260 co-acts with a machine locking device, as shown in Fig. 12. This device consists of a segment 23, having a number of 75 projections 24, provided at their outer ends with inclined surfaces 25 co-acting with the pin 6 carried by the initial keys. The segment 23 is loosely pivoted on rod 26 and is provided with a circular opening 27 through which passes rod 28 passing through a number of locking arms 29 also loosely journaled on the rod 26 and co-acting 80 with shoulders 30 (Figs. 1 and 7) of the levers 19. Shoulders 31 on the arms 29 are normally in the path of shoulders 30 but when an initial key is depressed the segment 23 is rocked upwardly, thereby elevating all of the arms 29 away from the shoulders 30, and, as far as this locking device 85 is concerned, permitting the operation of any one lever. Segments 32 (Fig. 10) co-act with pins 6 of the value keys in order to operate a latching lever 33 for the "No sale" lever, to prevent operation of this lever 90 whenever a value key is in its depressed position. The depression of a key rocks the segments upward and holds the same in moved position while remaining depressed. The segments 32 are connected by rod 34 95 with the lever 33, and this lever is provided with a shoulder 35 similar to the shoulders on levers 14 but co-acting with the shoulder 22 of the "No sale" lever only. The rod 12, previously described, passes through a slot 100 105 36 in the arm 33 so that while any key is being depressed the rocking movement of rod 12 will cause the lever 33 temporarily to move to locking position at the same time that the levers 14 are temporarily rocked to locking position. In order to release depressed keys at the end of each operation of the machine, the shaft 67 carries a pair of 110 cams 75 (Fig. 1) each having four projections 76, for engaging rollers 77 on bell 115 crank levers 78 at the end of each quarter turn of the shaft. The bell crank levers 78 carry a rod 79 extending across shoulders 80 of the key detent 7 and when actuated by cam 75 lift the detents and thus release the 120 depressed keys.

125 *Differential mechanism.*—The totalizers are differentially actuated by racks 51 (Fig. 1) in turn operated by slides 47 having graded steps and mounted in the carriage 55. These slides are first positioned by the action of value keys so that desired steps will engage the racks when the carriage is moved upwardly. Pivotally and loosely mounted on the shaft 49 in the rear of each 130

bank of keys is a stepped lever 37 (Fig. 2) rigid with a bevel gear 38, meshing with a bevel gear 39 on a shaft 40 passing from front to rear of the machine and journaled in suitable supporting frames. Fast on each shaft 40 is an arm 41 carrying a pin 43 extending through a slot 45 (Figs. 3 and 4) in one of the stepped slides 47. The keys are all depressible equal distances and as they are located different distances away from the pivot of lever 37 serve to rock differentially the lever 37. The differential movement is communicated through shafts 40 and arms 41 to the slides 47 which are provided with a plurality of series of shoulders 50 for co-acting with totalizer actuating racks 51. All of the slides are mounted on rollers 54 (Fig. 1) journaled on the carriage 55 which is slidably mounted on rods 237 and is elevated at each operation of any lever 19 by one of racks 56 (Fig. 7), driven by slides 18, and meshing with pinions 57 fast to a shaft 58 journaled in the side frames of the machine. The shaft 58 also carries a pair of pinions 59 meshing with racks 60 on the carriage 55. Accordingly at each operation of the machine after the differential slides have been properly set the carriage 55 is moved upwardly and returned on its upward movement differentially actuating the totalizer racks 51 by the stepped slides 47. Each set of totalizer racks 51 (Fig. 13) is normally held in its lower position by a spring 238 and is slidably mounted on a frame 61 loosely pivoted on the shaft 58. Springs 225 normally hold the frames 61 in a rearward position so that extensions 62 of the racks are not in the path of movement of steps 50 of slides 47. The levers 19 control means for rocking the frames 61 so that any desired set of racks 51 may be brought into operative relation with the set of slides 47 and its rack teeth 63 into the proper plane for engaging the totalizer actuating pinions 64 during the upward movement of the racks. To accomplish this movement, the frame 61 is provided with a forwardly extending arm 640 having a roller 65 co-acting with one of cams 66 loose on a shaft 67. Rollers 65 normally rest in notches 68 in the cam 66 and the cams are caused to make one-quarter of a revolution by the depression of any one of the operating levers 19. Accordingly four notches 68 are provided in cam 66 and in order to cause the quarter rotation of the cam by the operation of any one lever 19, the plates 15, operated by the levers, carry pawls 69 co-acting with notches 68 in the cams during the downward movement of the lever.

The racks 51 are held in mesh with the totalizer actuating pinions 64 by the cam 66 during the upward stroke of the racks. When the racks reach their upper positions,

one of the notches 68 arrives opposite the roller 65 permitting the springs 225 to rock the racks 51 out of mesh, the racks remaining free of the pinions 64 upon the return movement of the carriage 55. Overthrow 70 of levers 37 (Fig. 2) is prevented by levers 70 pivoted to the levers 37 by pins 71 and having shoulders 72 for engaging the key pins 6 when the keys reach their inner position. As the arc of the movement of the lever 70 is such that the shoulders 72 would cross the path of movement of the pins 6 immediately after the pins have reached their inner position, the levers 70 prevent further movement of the keys when the keys reach such position.

Totalizers.—The intermediate pinions 64 mesh with totalizer pinions 81 (Fig. 14) rigid with totalizer drums 82 and overthrow of the totalizer pinions is prevented by pawls 255 (Fig. 15), normally free to rock out of engagement with the totalizer pinions, but positively locked in engagement with the same when the carriage 55 reaches its upper position, by lugs 256 on the carriage engaging rollers 257 on a frame 258 hung from fixed pivots 259 and carrying a rod 260 for engagement with the tails of the pawls 255. Carrying operations are performed by pins 83 on the totalizer drums 90 engaging pawls 84 loosely pivoted on a rod 85. Each pawl 84 has a shoulder 86 normally in engagement with a shoulder 87 on an arm 88 loosely pivoted on shaft 89 and carrying a transfer pawl 90. When one of the pawls 84 is engaged by a pin 83, its shoulder 86 is carried away from the shoulder 87 of the arm 88, permitting a spring 91 to rock the arm 88 upwardly until the shoulder 87 comes to rest against shoulder 92 of the arm 84. The pawl 90 is thus rocked forwardly one tooth space of the intermediate gear 64 and a tail 93 of the pawl is moved into the path of one of a series of cams 94 on the shaft 95. The shaft 95 (Fig. 14) carries a pinion 96 meshing with an intermediate gear 97, in turn meshing with a gear 98 fast on the shaft 67, consequently when shaft 67 makes its one-quarter rotation on the return of carriage 55, any of the pawls 90 which are in tripped positions will be engaged by the cams 94 and returned to their original positions, thus rotating gears 64 which they engage the desired extra unit of movement. The pawls 84 follow the arms 88 during this movement under the action of springs 91 finally latching the arms 88 in their original positions when the shoulders 86 engage the shoulders 87. The totalizers may be simultaneously reset when the mechanism is in normal position by a knurled head 240 (Fig. 14) fast to the totalizer shaft 241 which is provided with the usual longitudinal groove 242.

(Fig. 15) for engaging pawls 243 on the totalizer pinions when the shaft is rotated in the normal direction of rotation of the totalizer. Before the shaft 241 can be rotated by the knurled head 240 it is necessary manually to rock a lever 244 (Fig. 13), fast to shaft 89, to carry a pin 245 mounted thereon out of a notch in disk 246, fast to the totalizer shaft. This rocking movement of shaft 89 is utilized for locking the operating mechanism of the machine, and for preventing the tripping of the transfer pawls during resetting operations. To prevent the tripping of transfer pawls the shaft 89 is provided with a groove 247 into which extend tongues 248 of the arms 88. The groove is wide enough to permit the rocking movement of the arms 88 at transferring operations but when the shaft 89 is rocked one side of the groove engages the tongues 248 holding the arms 88 in normal position and thus preventing the pawls 90 from moving into the paths of cams 94 and by the pawls 255 preventing backward rotation of the totalizer.

To lock the operating mechanism, shaft 89 carries an arm 250 having a pin 251 extending through a slot 252 in a cam 253 loosely pivoted on shaft 95. By this connection when shaft 89 is rocked the cam 253 engages a rod 254 of the locking frame 13 rocking the same into locking position. The notched disk 246 serves to hold the arm 244 in its moved position while the totalizers are being reset, but when the notch again comes into co-acting relation with pin 251, a spring 261 rocks the lever 244 to normal position, stopping rotation of the totalizer shaft when the totalizer pinions have reached zero position.

Indicator mechanism.—The indicators 195 are arranged in two sets of groups as shown in Fig. 3. Viewed from the front of the machine the group of transaction indicators 196 are at the left. To the right of the transaction indicators are the initial indicators 197. The three remaining groups 198 to the right are respectively for the dollars bank, the tens bank, and the units bank of value keys. The indicators for reading at the rear of the machine are in the same order as shown in Fig. 5. Each indicator tablet is provided with a lug 53 as before mentioned, and the lugs 53 extend inwardly into the vertical planes of movement of pins 52 carried by the slides 48. The slide 48 for the transaction indicators has a pin 52 for each group of transaction indicators, while the slide 48 for the initial indicators has a pin for each group of initial indicators. The slides for the value indicators are similarly each provided with two pins. All but the outside indicators

of each group have openings 199 as shown 65 in Fig. 4, through which the lugs 53 of the remaining indicators of the group pass in order to come over their respective pins 53. The openings in the indicators are of sufficient height to prevent interference between 70 the various indicators when in motion. Indicators are selected for operation by the keys and levers 19 through the differential rotation of shafts 40, as herein explained, which carry arms 42 having pins 44 extending through vertical slots 46 in the slides 48. The differential movement of the slides 48 brings the pins 52 beneath the lugs 200 of the indicators which it is desired to lift to exhibiting position. Then upon the forward movement of the carriage in which the slides are mounted, the selected indicators will be carried upwardly until lugs 200 on the indicators are above pins 201 in a reciprocating link 202 carried by a pair 85 of arms 203 pivoted by pins 204 to cross bars 205. The carriage 55 is provided with a pin 207 (Fig. 7) which, upon the rise of the carriage, engages the inclined edge 208 of a lug on a pawl 209 (Fig. 4) pivoted 90 to one of the links 202. The pawl is prevented from rocking in the direction in which it is urged on the upward movement of pin 207 by a pin 210 carried by one of the links 202 and passing through a slot 95 in the pawl. Accordingly the links 202 are rocked to the left releasing any of the indicators which are in their upper positions, until the pin 207 passes above the lug 211 of the pawl, when the link rocks to its normal position latching the lifted indicators in exhibiting position. On the return of carriage 55 pin 207 passes to the left of lug 211 slightly rocking pawl 209 to the right as permitted by the slot surrounding 100 the pin 210 but not disturbing links 202 which retain the lifted indicators in set positions.

Printing mechanism.—The printing mechanism is arranged to print complete records of each entered transaction on a record strip and a check strip, the latter of which is cut at each operation of the machine, the printed part falling on a suitable platform outside of the machine. The carriage 55 110 has mounted therein a short transverse shaft 100 (Fig. 17) on which are journaled a plurality of amount type carriers 101, one initial type carrier 102, and a class of transaction type carrier 103. Each type 115 carrier is rigid with a pinion 104 meshing with a rack 105, certain of which are cut in slides 47, and two others respectively meshing with the pinions rigid with the initial type carrier and the class of transaction type carrier, are cut in slides 106. These latter have no steps 50 as they are actuated by the bank of initial keys and 120 125

the levers 19, which do not operate totalizer elements. The slide 106 for the bank of initial keys is differentially actuated by one of the levers 37 (Fig. 2) the same as the slides 47 for the bank of value keys, but the slide 106 for the transaction levers 19 is shifted by cams 107 (Fig. 7) integral with the levers 19 and co-acting with rollers 108 on arms of a frame 109 which 10 is loose on the shaft 49. A bevel gear 110, shown at the left in Fig. 3, is fast to frame 109 so that differential movement of the frame will be communicated through the bevel gear 110 to a companion gear 111 fast 15 to one of the shafts 40 and by an arm 41 fast to this shaft, to one of the slides 106. The frame 109 is provided with a plurality 20 of arms 112 (Fig. 7) for engaging surfaces 113 of different heights on slides 18 thereby preventing overthrow of frame 109 as the slide which is moved forward will engage the arm 112 while the cam 107 which is operated will engage the roller 108.

The type wheels are mounted below a 25 platen 114 which is resiliently carried by rods 115 and 116 extending from the side frame of the machine (Figs. 17 and 20). It is provided with hook projections 117 resting on the rod 115, and elongated slots 30 118 through which the rod 116 passes. A plate 119 pivoted on the rod 115 and passing below rod 116 bears against a spring 120 between it and the platen thus providing the resilient mounting for the platen. A 35 check strip guide 121, also hung from the rods 115 and 116, is provided with an opening 122 through which the type wheels extend when making an impression. The check strip is wound on a roller 1231 (Fig. 40 22) carried by a stub shaft on the upper part of frame 124 and from this roller passes below a guide roller 424, above a guide frame 125, to an electrotype roller 126 and the co-acting impression roller 127, and 45 from these rollers the paper passes through the guide 121, between an ink ribbon 128 and the platen 114, over a knife 129. In order to drive the electrotype and impression rollers there is secured to the carriage 55 by a rod 130 a link 131 which moves vertically on the movement of the carriage and is guided by a fixed pin 132 passing through a slot 133 in the link. The link is provided 50 with a pin 134 passing through a slot 135 in a segment gear 136, which is loosely pivoted on a rod 137 and meshes with a gear 138 loose on a shaft 139 (Fig. 18) which has secured thereto the electrotype roller 126. The gear 138 is rigid with a clutch member 60 140 held by a spring in engagement with a second clutch member 141 fast to shaft 139. Thus the upward stroke of the segment gear 136 will merely idly rotate the gear 138 which is wider than the segment 136 so

as not to be disengaged therefrom by its 65 sidewise movement, but on the return of the segment 136 the clutch member 140, fixed to gear 138, engages the second clutch member 141 thereby causing the electrotype roller 126 to make one rotation, printing 70 whatever matter is contained thereon on the check strip and at the same time feeding the check strip forward the desired extent. This is after the impression takes place. The electrotype roller has the usual function 75 of printing advertising matter on the check strip. The impression roller 127 receives movement from the electrotype roller by being rigid with the gear wheel 142 meshing with a companion gear 143 fast to the 80 electrotype roller.

In order to prevent accidental rotation of the electrotype roller 126 or rotation thereof upon the upward movement of segment gear 136, the impression roller 127 is rigid 85 with the disk 173 cut away at 174 and into which cut away part extends the end of a lever 175. The rear end of this lever passes below the pin 130 in link 131, thereby when the machine is in normal position, preventing rotation of the impression roller 127 and the electrotype roller 126. The lever 175 remains in engagement with the disk 173 during the up stroke of link 131, but just as the link reaches its uppermost position, a pin 90 176 carried by the link engages the lever, rocking it out of engagement with the disk 173. The impression roller and the electrotype roller are then free to be rotated by the return movement of segment 136. On the 95 downward movement of link 131 pin 130 finally engages lever 175 and forces it again to a position locking the electro roller. The carriage 55 also carries a consecutive 100 number printing device 177 actuated when a pin 265 of its pawl carrying arm engages a fixed incline 266, and date printing wheels 178, all of the usual construction, and so they will not be described in detail. These 105 numbering and dating wheels are in position to print upon the check strip. For cutting the check strip, the shaft 67 which, as previously described, is caused to make a quarter of a rotation during the second half 110 of each operation of the machine, carries a cam 163 having four shoulders 164 for engaging the end 165 of a lever 166 pivoted by a pin 167 to the frame of the machine. The slide 168 rests on the forward end 169 of the lever 166 and at its upper end carries a knife 129 115 for cutting the printed part of the check strip from the remainder of the strip at each 120 operation of the machine. The knife 129 co-acts with a fixed knife 171. A spring 172 serves to return the slide 168 when the cam 163 permits the lever 166 to rock to normal 125 position.

The detail strip 153 (Fig. 19) passes from

1 supply roller 154 through a guide 155, between the two parts of the ink ribbon, as shown in Fig. 17, and around a roller 156 to a receiving roller 157. It is fed transversely 5 to the direction of the feed of the check strip by a pawl 158 (Fig. 18) engaging a ratchet wheel 159 fast to the receiving roller 157. The pawl 158 is carried by a lever 160 pivoted on the receiving roller shaft 161, 10 and is actuated by lugs 162 extending from the link 131. The endless ink ribbon 128 (Fig. 17) passes around a feed roller 144, co-acting with a companion feed roller 152, and around guiding rollers 145, 146, and 15 147. The feed roller 144 is rotated by a pawl 148 carried by a spring pressed lever 149 which is rocked around the pivot 150 of the feed roller when engaged by the upper end of a slot 151 and link 131 when the link 20 is returning to its normal position.

25 *Multiple drawer mechanism.*—At the rear of the machine, below and to the rear of the slides 18, is a transverse shaft 217 on which are loosely journaled a plurality of levers 218, (Fig. 1 and Fig. 8, Sheet 8) connected by sleeves 219, levers 220, and links 221, to multiple drawer latching devices 222. When one of the slides 18 engages its respective lever 218, it causes the lifting of the corresponding link 221 and releases the desired one of the cash drawers 236. It may be noted that the cash drawers are released according to the class of transaction which is recorded and not as usual according to the depressed 35 clerk's initial key. Various benefits result from this arrangement, notably in auditing, because the amount of cash in the "Cash" and "Received on account" drawers will or should equal the amount indicated by the 40 respective totalizers. Also the addition of the amount represented by the "Paid out" totalizer and the amount of cash in the "Paid out" drawer should agree with the total amount put in the drawer for such 45 transactions. By the provision of these separate transaction drawers mistakes are traceable to at least the class of transaction and when "charge" sales are entered none of the drawers containing cash become 50 cessible.

55 *Operation.*—To enter a transaction the value keys representing the amount of the transaction and one of the clerk's initial keys are depressed, the latter, unlatching all 29 of the levers 19 by lifting the latching device (Fig. 12) out of engagement with the shoulders 30 (Fig. 7) on levers 19. One of the levers 19, according to the class of transaction to be entered, is then operated to complete 60 the operation of the machine. The depression of the keys causes the shifting of corresponding slides 47 (Fig. 3) and 48 (Fig. 4) by differentially rocking levers 37 and thereby the shafts 40 which are connected to

the slides by arms 41 and 42. The differential movement of slides 47 through the racks 105 properly sets the amount and initial type carriers, and then when one of the transaction levers is operated the transaction type carrier is set by the corresponding slide 47 70 and the transaction indicators are selected by the corresponding slide 48. The transaction slides 47 and 48 are differentially shifted by the camming action of levers 19 on the frame 109 loose on shaft 49 (Fig. 7). 75 The bevel gear 110 fast to the frame 109 communicates its differential movement to the bevel gear 111 on the inner end of the shaft 40 which is connected to the transaction slides. The downward movement of 80 the operated lever 19 first by rocking the plate 15 (Figs. 1 and 13) rocks the corresponding set of totalizer actuating racks 51 into the proper vertical position for being 85 engaged by the stepped slides 47 and for meshing with the totalizer pinions. The arms 62 of the racks 51 are normally out of the path of movement of slides 47, as shown in Fig. 1. Accordingly when the stepped slides are lifted upwardly by the upward 90 movement of carriage 55 only this selected set of actuators 51 will be operated and the desired totalizer added to. The upward movement of the carriage is accomplished by a lever 19 through its slide 18 meshing with 95 a pinion fast to shaft 58 (Fig. 7) which carries pinions meshing with racks in the frames 55. When the carriage reaches its upper position, the printed records are made on the detail strip and the check strip. 100 Then on the return of the carriage the check strip is fed forwardly by the segment gear 136 and the detail strip is fed by the pawl 158 (Fig. 18). Finally, the cam 163 (Fig. 17) by engaging the lever 166 lifts the knife 105 129 thereby cutting the printed check from the remainder of the strip. The cash drawer corresponding to the operated lever 19 is allowed to move to its open position when the lever reaches its lowest position, at which 110 time a slide 18 engages one of the arms 218 (Fig. 1) connected to the drawer latching devices.

115 While the form of mechanism herein shown and described is admirably adapted to fulfil the objects primarily stated it is to be understood that it is not intended to confine the invention to the one form of embodiment herein shown and described as it is susceptible of embodiment in various 120 forms all coming within the scope of the claims which follow.

125 What is claimed is:

1. In a machine of the class described, the combination with a plurality of totalizers, 125 of a plurality of sets of totalizer actuating racks, frames in which the racks are slidably mounted, a carriage, a set of slides

mounted in the carriage having a plurality of series of graduated steps, means for differentially setting said slides, means for rocking said frames to carry the racks into and out of engaging position with the totalizers, and means for moving the carriage to cause the slides to actuate the racks that are in engaging position.

2. In a machine of the class described, the combination with a totalizer, and actuating racks therefor, of denominational graduated slides positioned under said racks, banks of keys, connections from said keys constructed to give said slides differential lateral movements, and means for giving all said slides movements of invariable extent in a substantially vertical direction, whereby to actuate said racks.

3. In a machine of the class described, the combination with a totalizer, and actuating racks therefor, of denominational graduated slides positioned adjacent to said racks, banks of keys, connections from said keys positioned to give said slides differential movements in a direction substantially at right angles to the direction of movement of said racks, and means for giving all said slides movements of invariable extent in the direction of movement of said racks, whereby to actuate said racks.

4. In a machine of the class described, the combination with a totalizer, and actuating racks therefor, of denominational graduated slides having slots and positioned adjacent said racks, banks of keys, connections from said keys, including elements riding in said slots, constructed to give said slides differential lateral movements, and means for giving all said slides movements of invariable extent in a substantially vertical direction whereby to actuate said racks.

5. In a machine of the class described, the combination with a totalizer, and actuating racks therefor, of denominational graduated slides having slots and positioned adjacent said racks, banks of keys, connections from said keys, including elements riding in said slots, constructed to give said slides differential movements in a direction substantially at right angles to the direction of movement of said racks, and means for giving all said slides movements of invariable extent in a direction substantially the same as is the movement of said racks whereby to actuate said racks.

6. In a machine of the class described, the combination with a totalizer, and actuating racks therefor, of denominational graduated slides positioned adjacent said racks, banks of keys, lever arms actuated by said keys, connections from said lever arms to move said slides differentially in one direction, a hand lever, and connections from said lever constructed to give said slides movements

of invariable extent in another direction, and thereby to actuate said racks.

7. In a machine of the class described, the combination with a totalizer, and actuating racks therefor, of denominational graduated slides positioned adjacent said racks, a carriage in which said slides are mounted, banks of keys, connections from said keys constructed to adjust said slides differentially on said carriage, in one direction and means for giving said carriage movements of invariable extent in a direction substantially at right angles to said first direction, thereby causing said slides to engage and actuate said racks.

8. In a machine of the class described, the combination with a totalizer, and actuating racks therefor, of denominational graduated slides having slots and positioned adjacent said racks, a carriage in which said slides are mounted, banks of keys, connections from said keys including elements riding in said slots, constructed to adjust said slides differentially in one direction, a hand lever, and connections from said lever constructed to give said carriage movements of invariable extent in another direction, whereby to actuate said racks.

9. In a machine of the class described, the combination with a totalizer, of an actuating rack for the totalizer, a guide slidably carrying said rack, a movable member, means for operating said member, and means for moving said guide constructed to position the rack in the path of said movable member, whereby the rack will actuate the totalizer.

10. In a machine of the class described, the combination with a plurality of totalizers, of a plurality of sets of actuating racks for the totalizers, a guide slidably carrying each of said sets, movable members, means for operating said members, means for moving any one of said guides constructed to position its set of racks in the path of said movable members whereby the racks will actuate the totalizers.

11. In a machine of the class described, the combination with a totalizer, of a set of totalizer actuating racks, a frame in which the racks are slidably mounted, a carriage, a set of slides mounted in the carriage and having a series of graduated steps, means for differentially setting said slides, and means for moving the carriage to cause the slides to actuate the racks.

12. In a machine of the class described, the combination with a plurality of accounting devices, of actuating mechanism for the accounting devices, value keys controlling the actuating mechanism, a plurality of operating levers connected to drive the actuating mechanism, connections from certain of said levers constructed to select account-

ing devices for operation, and means, operated by the value keys, for preventing operation of one of said levers.

13. In a machine of the class described, 5 the combination with a series of operating mechanisms, of a recording mechanism manipulative devices capable of preliminary adjustment to determine the amount to be recorded upon an operation of certain of 10 said operating mechanisms and devices controlled by said manipulative devices to lock one of said operating mechanisms when any one of the manipulative devices is adjusted.

14. In a machine of the class described, 15 the combination with a main operating mechanism, of a "no sale" lever connected to actuate said mechanism, a disk, having a depression, and connections to operate said disk from said "no sale" lever, value keys, 20 an arm, constructed to engage said disk at said depression, and connections from said value keys serving to actuate said arm and thereby to lock said lever against operation.

15. In a machine of the class described, 25 the combination with two series of groups of tablet indicators, the tablets of each group being arranged one before the other, of a slide, projections on said slide, means for differentially moving said slide and its 30 projections to select like indicators in corresponding groups of the two series, and means for lifting the slide to expose the selected indicators.

16. In a machine of the class described, 35 the combination with a plurality of accounting devices, of separate driving mechanism for each of said devices, keys common to and controlling all the driving mechanisms, a plurality of cash drawers corresponding 40 to the accounting devices, drawer retaining devices, a plurality of operating handles having connections to the driving mechanisms, and separate connections between the operating handles and the corresponding 45 drawer retaining devices.

17. In a machine of the class described, the combination with a main operating mechanism including a rocking drive shaft, means for rocking the said drive shaft, of 50 two ratchet wheels fast to the shaft, a pair of pawls co-acting with the ratchets, means, controlled by said shaft, for alternately rocking the pawls at the limits of movement of said shaft, a second drive shaft, means 55 for operating said second shaft, and devices normally preventing operation of said second shaft, with connections whereby said pawl rocking means may disable said preventing devices.

60 18. In a machine of the class described, the combination with a main operating mechanism including a drive shaft, means for operating said drive shaft, a second drive shaft, means for operating said sec-

ond drive shaft, means normally preventing 65 operation of said second drive shaft, and means operable with said first mentioned drive shaft for disabling said preventing means.

19. In a machine of the class described, 70 the combination with a plurality of accounting devices, and actuating mechanism therefor, of a plurality of driving devices for said actuating mechanism, members, having differentially graded surfaces, and connecting 75 said driving devices and said actuating mechanism, graded camming surfaces on said driving devices, a type carrier and indicator setting shaft, a set of arms on said shaft constructed to be driven by said camming surfaces, and a second set of arms on said shaft constructed to engage said graded surfaces.

20. In a machine of the class described, 80 the combination with a movable frame, of a plurality of type carriers and actuating devices therefor mounted in said frame, a platen, means for moving the frame for the purpose of carrying the type carriers against the platen thereby taking an impression 90 upon a record strip, and a totalizer actuated under the control of the type carriers actuating devices when the frame carrying said actuating devices is moved.

21. In a machine of the class described, 95 the combination with a movable frame, of a plurality of type carriers and actuating devices therefor mounted in said frame, means for differentially adjusting the actuating devices and thereby the type carriers, a platen, 100 means for moving the frame thereby carrying the type carriers against the platen for the purpose of listing items on a record strip, and a totalizer actuated under the control of the actuating devices for the type 105 carriers upon the movement of the frame carrying said actuating devices.

22. In a machine of the class described, the combination with a series of totalizers, 110 of a series of groups of actuators, one group for each totalizer, a series of main operating devices, one for each totalizer, and means controlled by the main operating devices for selecting the totalizer to be actuated upon an operation of one of said main operating devices.

23. In a machine of the class described, the combination with a series of totalizers, 115 of a series of keys common to and controlling the operation of all of said totalizers, a series of main operating devices, one for each totalizer, and means controlled by the operation of one of said main operating devices for selecting and operating its appropriate totalizer.

24. In a machine of the class described, 120 the combination with a plurality of totalizers, of a set of actuators for each to-

- talizer normally out of coöperative relation therewith, a driving device for the actuators of each totalizer, manipulative devices, and means controlled by each driving device for establishing coöperative relation between the actuators driven thereby and the companion totalizer and then actuating the totalizer an extent determined by the operated manipulative devices.
- 10 25. In a machine of the class described, the combination with a plurality of totalizers, of a set of actuators for each totalizer normally out of engagement therewith, a driving device for the actuators of each 75 totalizer, manipulative devices, and means controlled by each driving device for moving the actuators driven thereby into engagement with the companion totalizer and then actuating the totalizer an extent determined by the operated manipulative devices.
- 15 26. In a machine of the class described, the combination with a plurality of totalizers, of a set of actuators for each totalizer normally out of coöperative relation therewith, graduated elements for driving said actuators, manipulative devices for differentially adjusting said elements, a plurality of main operating devices one for each totalizer, and means controlled by each operating device for establishing coöperative relation between the corresponding totalizer and its set of actuators and driving the latter by the graduated elements an extent determined by the operated manipulative devices. 80
- 20 27. In a machine of the class described, the combination with a plurality of totalizers, of a set of actuators for each totalizer normally out of coöperative relation therewith, graduated elements for driving said actuators, manipulative devices for differentially adjusting said elements, a plurality of main operating devices one for each totalizer, and means controlled by each operating device for establishing coöperative relation between the corresponding totalizer and its set of actuators and driving the latter by the graduated elements an extent determined by the operated manipulative devices. 85
- 25 28. In a machine of the class described, the combination with a plurality of totalizers, of a set of actuators for each totalizer normally out of coöperative relation therewith, graduated elements for driving said actuators, manipulative devices for differentially adjusting said elements, a plurality of main operating devices one for each totalizer, and means controlled by each operating device for establishing coöperative relation between the corresponding totalizer and its set of actuators and driving the latter by the graduated elements an extent determined by the operated manipulative devices. 90
- 30 29. In a machine of the class described, the combination with a plurality of totalizers, of a set of actuators for each totalizer normally out of coöperative relation therewith, graduated elements for driving said actuators, the latter being normally out of the plane of movement of said elements, amount manipulative devices for differentially adjusting said elements, a plurality of main operating devices one for each totalizer, and means controlled by each operating device for establishing coöperative relation between the totalizer corresponding to the operated device and its set of actuators thereby bringing said actuators into the plane of movement of the graduated elements whereby the selected totalizer will be actuated an extent determined by operated amount manipulative devices. 95
- 35 30. In a machine of the class described, the combination with a plurality of totalizers, of a set of actuators for each totalizer normally out of coöperative relation therewith, graduated elements for driving said actuators, manipulative devices for differentially adjusting said elements, a plurality of main operating devices one for each totalizer, and means controlled by each operating device for moving the corresponding set of actuators into coöperative relation with the companion totalizer and driving the engaged actuators by the graduated elements an extent determined by the operated manipulative devices. 100
- 40 31. In a machine of the class described, the combination with a totalizer, of actuators therefor, an invariably moved driving mechanism, manipulative devices, and elements intermediate the actuators and the driving mechanism differentially adjustable in one direction by the manipulative devices as a preliminary to being moved an invariably distance in another direction by the driving mechanism to differentially operate the totalizer actuators, and means for giving said elements an invariable movement. 105
- 45 32. In a machine of the class described, the combination with an accounting device and actuators therefor, of graduated slides positioned under said actuators; a plurality of keys, connections whereby the graduated slides may be differentially positioned by 110 operation of said keys, and means for giving all of the slides an invariable movement to differentially operate the actuators. 115
- 50 33. In a machine of the class described, the combination with a main driving mechanism, of a plurality of totalizers, a set of actuators for each totalizer normally out of engagement therewith, a plurality of operat- 120
- 55 125

ing devices corresponding to the totalizers and independently operable to give the driving mechanism an invariable extent of movement, value keys common to all of the 5 actuators, a plurality of members intermediate the actuators and the main driving mechanism, said members being differentially adjustable by means of the value keys and invariably moved on all operations of 10 the driving mechanism, and means rendered effective by an operation of one of the afore-

said operating devices for moving the corresponding set of actuators into engagement with its totalizer and into the path of invariable movement of the differentially adjusted 15 devices.

In testimony whereof I affix my signature in the presence of two witnesses.

FREDERICK L. FULLER.
